Richard J. Cook

UNITED STATES PATENT OFFICE.

CHARLES C. DOSE, OF SEATTLE, WASHINGTON, ASSIGNOR TO PERFECLITE MANUFACTURING CO.

LIGHTING FIXTURE.

Application filed October 20, 1920. Serial No. 418,224.

To all whom it may concern:

Be it known that I, CHARLES C. Dose, a citizen of the United States, and resident of the city of Seattle, county of King, State of Washington, have invented certain new and useful Improvements in Lighting Fixtures, of which the following is a specification.

This invention relates to improvements in lighting fixtures, and more particularly to fixtures of that type characterized as being dust proof, and wherein a complete fixture consists of a closed cover portion, a translucent bowl suspended therefrom in a dust proof connection, a reflector plate that is located within the cover and an incandescent electric lamp that is placed within the bowl beneath the reflector; all of which is suspended by the lamp cord.

The principal object of the present invention is to provide a fixture of the above character, that will be neat and attractive in appearance, which will be dust proof, and wherein the several parts are so connected that they may be easily and quickly assembled or disassembled.

Another object of the invention is to provide means whereby a circulation of air is permitted about the reflector and within the bowl for the purpose of preventing overheating by the lamp.

A further object of the invention resides in the means and manner whereby the bowl is supported from the cover portion.

In accomplishing these and other objects of the invention, I have provided the improved details of construction, the preferred forms of which are illustrated in the accompanying drawings, wherein—

Figure 1 is a view, partly in elevation and partly in central, vertical section, of a lighting fixture embodying the present invention.

Figure 2 is a detail, perspective view of the cover portion, the reflecting plate and the locking ring whereby the bowl is suspended from the cover; the parts being shown in dis-assembled relation.

Figure 3 is an enlarged sectional view, taken substantially on the line 3—3 in Figure 1, showing the means for yieldingly holding the locking ring in functional position on the cover.

Figure 4 is an enlarged detail sectional view, of a part of the cover, the locking ring, the reflector and bowl in assembled relation.

Referring more in detail to the several views of the drawings, wherein like reference numerals designate like parts—

1 designates the cover portion of the device, this preferably being of metal, of a somewhat conical shape and provided at its apex with a small aperture 2 for receiving the lamp cord 3 whereby electric current is supplied to the lamp 4 and also whereby the fixture may be suspended.

At its lower periphery the cover is provided with a flange 5 and seated within this is a reflector 6, which is of such character as to cast the rays of light from the lamp 4 downwardly. This reflector consists of a single plate provided centrally with an opening 7 through which the lamp socket 8 may extend the opening in the reflector 6 being of such size as to frictionally engage the socket when inserted and thereby serve to anchor the bulb 4 against displacement and about the opening 7 with a plurality of small apertures 9 whereby a circulation of air within the bowl and cover is permitted.

Suspended from the cover portion and enclosing the lamp 4, is a closed, translucent bowl 10. This is provided about its upper edge with an out-turned peripheral flange 11 which is adapted to fit within the flange of the cover 1 and to be locked therein to support the bowl and reflector plate 6 by means of a locking ring 12 which is removably applied to the flange 5.

The ring 12 is of such size that it will snugly receive the flange 5, and at its lower edge has an outwardly pressed annular groove, or channel, 14 and an inwardly extending annular rim 15 which is adapted to supportingly engage the flange 11 of the bowl 10. The ring is locked in place, when applied to the cover, by means of a bayonet joint connection; the flange 5 of the cover having a plurality of bosses 16 pressed outwardly therefrom which are adapted to be moved downwardly through cooperatively located grooves 17 in the ring 12 and into the channel 14 at its lower edge whereupon, by partially rotating the ring on the cover, the parts will be securely locked together.

Stop members 18 are fixed in the channel 14 at one side of the junction with the grooves 17, and at the opposite side are inclined wedge pads 19 of leather, or the like, against which the bosses 16 may be turned

to yieldingly hold the parts in functional, and locked relation.

By this particular construction it will be seen that the cover and bowl are joined together in a dust proof connection and that the bowl and reflector are held in place by a locking ring that can be easily and quickly removed to permit access to the lamp and reflector when necessary.

10 It is also apparent that the perforations 9 of the reflector will permit a certain desired circulation of air within the cover and bowl which will prevent overheating of the parts adjacent the lamp.

15 Having thus described my invention, what I claim as new therein, and desire to secure by Letters Patent is:

A lighting fixture of the character described comprising a somewhat conically shaped cover portion provided with a down-turned peripheral flange having bosses pressed outwardly therefrom, a translucent

bowl provided with an out-turned flange at its periphery and adapted to fit snugly within the cover flange, a perforated reflector plate disposed within the cover and supported upon the edge of said bowl, a lamp suspended within said bowl and anchored centrally by said reflector plate, and a locking ring fitted about the cover flange, having bayonet slots for receiving bosses of the cover flange to removably secure the ring to the flange and having an in-turned rim at its lower edge whereupon said bowl flange rests to support the bowl from the cover; 25 said boss receiving channels in said ring having yieldable means secured therein against which said bosses may engage to 30 frictionally and yieldingly retain the ring in locking relation.

40 Signed at Seattle, Washington, this 15th day of October, 1920.

CHARLES C. DOSE.
